UNITED STATES PATENT OFFICE.

ROSS M. G. PHILLIPS, OF WEST HAVEN, CONNECTICUT.

AUTOMATIC COOKING APPARATUS.

1,161,525.

Specification of Letters Patent. Patented Nov. 23, 1915.

Application filed November 7, 1914. Serial No. 870,783.

To all whom it may concern:

Be it known that I, Ross M. G. PHILLIPS, a citizen of the United States, residing at West Haven, in the county of New Haven and State of Connecticut, have invented a new and useful Improvement in Automatic Cooking Apparatus; and I do hereby declare the following, when taken in connection with the accompanying drawings and the characters of reference marked thereon, to be a full, clear, and exact description of the same and which said drawings constitute part of this application, and represent, in—

Figure 1 a view in front elevation of one form which an automatic cooking apparatus constructed in accordance with my invention may assume. Fig. 2 a view thereof in right hand side elevation, with the upper rear corner of the cooking compartment or oven broken away to show the egress draft-passage and its damper or closure. Fig. 3 a view in horizontal section on the line *c-d* of Fig. 1. Fig. 4 a broken detail view through the bottom of the cooking compartment to show its ingress draft-passage and the oscillating shutter employed to close the same. Fig. 5 a detail view showing a shutter-lifter. Fig. 6 a broken detail view of the neck and feeding mechanism of the oil-tank. Fig. 7 a broken view in front elevation of one of the modified forms which my automatic cooking apparatus may assume. Fig. 8 a broken view thereof in horizontal section on the line *a-b* of Fig. 7, on an enlarged scale. Fig. 9 a broken view in side elevation of the parts shown in Fig. 8.

My invention relates to an improvement in liquid fuel or oil-burning automatic cooking apparatus of the type in which the burner is bodily raised and lowered for changing its position with respect to the level of the oil or other liquid fuel, the object being to provide a simple, convenient and reliable cooking apparatus of the type described.

In carrying out my invention, I mount a burner-base 2 carrying a burner-casing 3 upon the upper end of a vertically movable feed-tube 4 the lower end of which moves up and down in a gland 5 upon the upper end of a vertical oil-supply pipe 6 connected by an elbow 7 with a similar pipe 8 leading from the feed-cup 9 into which oil 55 is fed from a removable oil-tank 10 as will be described later on. The burner which,

broadly speaking, is represented by the base 2 and casing 3, is raised and lowered by means of a three-armed lever comprising a lifting-arm 11, a journal 12 and an operating-arm 13, the arm 11 being furnished with a fork 14 the slot of which receives a pin 15 in a lug 16 offsetting from a sleeve 17 depending from the burner-base 2. The journal-arm 12 aforesaid is mounted in the upper end of a bracket 18 secured to a drip-pan 19 mounted between the four legs 20 at the corners of a double-walled cooking compartment or oven 21. The operating-arm 13 of the said lever is connected by a vertically arranged link 22 with a short crank-arm 23 located upon the outer end of a rock-shaft 24 journaled in bearings 25, 25, applied to the back of the cooking compartment 21. At its inner end the rock-shaft 24 is furnished with a crank-arm 26 connected with the lower end of a long link 27 the upper end of which is connected with a crank-arm 28 upon a rock-shaft 29 journaled at its ends in a flue-pipe fitting 30 projecting from the upper rear corner of the compartment 21. The said shaft 29 carries a lifting-finger 31 engaged with the bail 32 of a damper or closure 33 located in a housing 34 set within the upper rear corner of the compartment 21 over a casing 35 therein containing an egress draft-passage 36 which is normally closed by the damper 33 which carries a small vent 37.

Directly above the vertically movable burner comprising, as shown, the parts 2 and 3, I locate a large circular ingress draft-passage 38 (Fig. 4), in the center of the bottom of the cooking compartment 21. This passage is closed by means of a disk-shaped shutter or closure 39 swinging in the horizontal plane and furnished at its right hand end with a depending sleeve 40 by means of which it is pivotally mounted upon a stud 41 having its lower end threaded for the reception of a retaining nut 42 and depending from a burner-seat casing 43 applied to the bottom of the cooking compartment 21 and entering the lower edge of the ring 44 forming the ingress draft-passage 38. For insuring the sealing of the said passage 38, I employ, as shown, two shutter-lifters in the form of spring-fingers 45 (Figs. 3, 4 and 5) mounted on blocks 46 fastened to the bottom of the compartment 21, the said spring-fingers 45 being respectively placed so that the shank 47 and lug 48 of the shutter 39 will

ride over them just as the same is moving into its closed position under the influence of a helical spring 49 attached to the bottom of the compartment 21 and to an arm 50 offsetting from the sleeve 40 as clearly shown in Fig. 3. The said shutter 39 is swung into its open position against the tension of the spring 49, by means of a link 51 interposed between the arm 52 of a bell-crank lever 53 turning on a rock-shaft 54 journaled in a bearing 55 fastened to the right hand side of the cooking-compartment 21. At its upper end the rock-shaft 54 is furnished with a short arm 56 connected by a link 57 with a crank-arm 58 at the extreme outer end of the rock-shaft 24 which latter is thus operated in concert with the shutter 39 so that the shutter 39 and damper 33 will be simultaneously operated for opening and closing 20 the ingress draft-passage 38 and the egress draft-passage 36 respectively.

The arm 59 of the bell-crank lever 53 is connected by a link 60 with the rear end of a horizontally arranged sliding latch-rod 61 furnished at its projecting forward end with a handle 62 by means of which the burner is lowered and the shutter 39 and the damper 33 are manually opened. The said rod 61 is formed with a notch 63 receiving a lug 64 on a latch 65 furnished at its outer end with a forestalling-arm 66 and hung upon a pin 67 in the lower end of the case 68 of a timing-mechanism applied by brackets 69 to the right hand side of the cooking compartment 21. The timing mechanism may be of any approved construction, and is fully illustrated in my co-pending application Serial No. 782,445, filed August 1, 1913, Timing mechanism.

40 As far as shown herein, the timing-mechanism is furnished with a setting-lever 70 having a handle 71 and mounted upon the projecting outer end of an arbor 72 whereby the lever is supported in front of the case 68. At its upper end, the lever 70 is formed with a pointer 73 sweeping over a graduated dial 74 applied to the front of the case 68. A timing-disk 75 mounted upon the arbor 72 is formed with a timing-slot 76 receiving a timing-pin 77 in a lever 78 hung upon a pin 79 and furnished at its opposite end with a handle 80 passing through a segmental slot 81 in the case 68. The lever 78 is connected by a lifting-link 82 with the latch 65, the lower end of the link 82 being furnished with a slot 83 receiving a pin 84 upon the lever 65 which is thus permitted to be lifted by its forestalling handle 66 to forestall or anticipate the action of the timing-mechanism in case it should be desired to operate the shutter and damper, and lower the burner before the expiration of the time provided for in setting the timing-mechanism. A helical spring 85 connected with the lever 65 78 operates to smartly lift the same when

the reverse rotation of the timing-disk 75 has brought its timing-slot 75 into registration with the pin 77 in the lever 78. By setting the lever 78 with regard to the dial 74, the apparatus may have its burner lifted 70 and hence extinguished and its ingress and egress passages 38 and 36 closed at any predetermined time.

Liquid fuel is supplied to the apparatus from a cup 9 (Figs. 1 and 6) receiving a neck 86 projecting from the periphery of the tank 10 and closed by a threaded cap 87 having a valve-seat 88 and provided upon its inner face with a concentric valve-chamber 89 having inlet-ports 90 and inclosing a valve 91 mounted upon a stem 92 encircled by a spring 93 located within the chamber 89 and exerting a constant effort to seat the valve 91 upon the seat 88 so that when the tank 10 is removed for refilling, the valve 80 will automatically act to prevent the escape of any oil. The valve-stem 92, however, is adapted in length so that when the tank is in place as shown in Fig. 6, the stem 92 will engage with the bottom of the cup 9 90 and lift the valve 91 above its seat 88 and hold the same in that position. The normal level of oil in the cup 9 is represented by the line 94, to which the oil will be held by the pressure of the atmosphere. Now as the oil 95 is drawn off from the cup, bubbles of air rising through the open valve-seat 88 into the tank 10 will permit more oil to feed from the tank into the cup. I do not, however, limit myself to any particular oil-tank or 100 feeding mechanism therefor.

As a condition precedent to the setting of the apparatus, the timing-mechanism must be set by its lever 70 after which the handle 62 is grasped and the rod 61 drawn forward until the lug 84 of the latch 65 enters the notch 63 in the rod 61, which is drawn forward against the tension of a helical spring 95 connected with it and supplying motive power for closing the shutter 39 and the damper 33 and for raising the burner so as to extinguish the same. As the handle 62 is pulled forward, the shutter 39 is swung open for opening the ingress draft-passage 38. At the same time and by the same means, the damper 33 is lifted to open the egress draft-passage 36. At the same time, also, the burner is lowered by the three-armed lever comprising the arms 11, 12 and 13. In this connection I should state that the burner and oil-cup 9 are relatively arranged so that the wick-chamber of the burner will be flooded with oil when the burner is in its lowered position and drained clear of oil when the burner is in its elevated position, so that it is only necessary to lift the burner to extinguish the light. The burner on being lowered is immediately flooded with oil and may then be lifted. The food will now be placed in the cooking 115 120 125 130

compartment 21 through its double-walled door 96 which is furnished with a handle 97. The flame from the burner and the products of combustion rise through the ingress 5 draft-passage 38 and pass out through the egress draft-passage 36. At the termination of the period to which the timing apparatus was set, the timing-pin 77 will enter the slot 76 and the spring 85 will act to lift the link 10 82 which will in turn lift the lug 64 of the latch 65 out of the notch 63 when the spring 95 will act to swing the shutter 39 into its closed position and permit the damper 33 to seat itself over the egress passage 36 and 15 also lift the burner into its elevated position in which it is drained of oil and extinguished, as explained. The cooking of the food is now continued until the apparatus has lost its heat by radiation, which will be 20 slow on account of the insulation of the cooking compartment and its door.

In the modified construction shown by Figs. 7 to 9 inclusive, a burner-base 98 carrying a burner-casing 99, is mounted upon 25 a vertically movable liquid fuel feed-pipe 100 passing through a gland 101 in the upper end of an oil-supply pipe 102 connected by an elbow 103 with an oil-supply pipe 104 leading from an oil-cup 105 carrying an 30 oil-tank 106. The burner comprising the parts 98 and 99, is raised and lowered by means of a rack 107 receiving the teeth of a wheel 108 mounted upon a shaft 109 journaled in a sleeve-like bearing 110 having 35 lugs 111 receiving a screw 112 by means of which the said bearing is clamped upon the pipe 102. As shown in Fig. 9, the bearing 110 has a lug 113 for the guidance of the lower end of the rack 107. At its 40 rear end, the shaft 109 is furnished with a crank-arm 114, connected by a long link 115 with a crank-arm 116 at the lower end of a rock-shaft 117 furnished at its upper end with a crank-arm 118 suitably connected 45 with a latch-rod 119 corresponding to the rod 61 aforesaid and furnished at its forward end with a handle 120. The said

latch-rod 119 is controlled by a timing-mechanism designated by the numeral 121. By pulling forward on the handle 120, the 50 burner is lowered by means of the wheel 108 which is rotated for raising the burner to extinguish it when the timing-mechanism releases the train of parts between it and the said wheel 108, by a spring, not shown, but 55 corresponding to the spring 95.

I claim:—

1. In an automatic cooking apparatus, the combination with a cooking compartment having an ingress draft-passage and an 60 egress draft-passage, of a closure for the said egress draft-passage, a liquid fuel-tank, a vertically movable burner connected with the said tank and adapted to be raised and lowered with respect thereto, whereby, it is 65 flooded with liquid fuel and drained thereof, means for automatically controlling the raising of the burner into its drained position and the closing of the said closure, and means for manually opening the said closure 70 and controlling the lowering of the burner into its flooded position.

2. In an automatic cooking apparatus, the combination with a cooking compartment or oven having an ingress draft-passage and an 75 egress draft-passage, closures for the said passages, a liquid fuel tank, a vertically movable burner connected with the said tank and raised and lowered with respect to the said tank whereby it is flooded with liquid 80 fuel and drained thereof, means for automatically controlling the closure of the said passages and the raising of the burner, and means for manually opening the said closures and controlling the lowering of the 85 burner.

In testimony whereof, I have signed this specification in the presence of two subscribing witnesses.

ROSS M. G. PHILLIPS.
